ATHLETIC GIRDLE

Harry C. Gingrich, Pottstown, Pa., assignor to
Iris Knitting Corporation, Pottstown, Pa., a
corporation of Pennsylvania

Application June 27, 1934, Serial No. 732,653

1 Claim. (Cl. 128—159)

The principal object of the present invention is to provide a combined abdominal supporter and suspensory, for the use of athletes and others, which shall be efficient, comfortable and attractive, and yet comparatively inexpensive.

Other objects of the invention will appear from the following description.

Generally stated, the invention comprises an elongated tube of elastic knitted fabric including 10 buried rubber strands and having portions of different degrees of elasticity, of which one is a waist belt and of which the other is an abdominal supporter, and is bifurcated back and front to provide leg openings, and a strip of relatively 15 inelastic fabric having pointed ends secured to the edges of the bifurcations and provided with darts extending from the points of union of the edges of the bifurcations with the body of the strip, providing a suspensory pouch.

20 The invention also comprises the improvements to be presently described and finally claimed.

In the following description, reference will be made to the accompanying drawing forming part 25 hereof and in which:

Figure 1 is a view of a combined abdominal supporter and suspensory embodying features of the invention.

Figure 2 is a view of the same in distended 30 position as occurs in use, and it is either back or front view, since the back and front are alike, and

Fig. 3 is a plan view showing a part detached and indicating in dotted lines the original shape 35 thereof and indicating in full lines the finished product.

In the drawing, there is shown an elongated tube of elastic knitted fabric having buried strands of rubber ranging around the same. The portions 1 and 2 of the tube are of different degrees of elasticity, and the portion 1 is more elastic and is a waist belt. The portion 2 is an abdominal supporter and is axially bifurcated or slashed at both the back and front. 3 is a strip of relatively inelastic fabric and its ends 4 are pointed and secured to the edges 6 of the bifurcations. The strip is provided with four darts 7, extending from the points 8 of the union of the edges of the bifurcations with the body of the strip. The strip provides a suspensory pouch and it may well be knitted of soft yarn.

It will be obvious to those skilled in the art to which the invention relates that modifications may be made in details of construction and arrangement in matters of mere form without departing from the spirit of the invention which is 20 not limited in respect to such matters or otherwise than as the prior art and the appended claim may require.

I claim:—

An athletic girdle comprising an elongated tube 25 of elastic fabric having portions of different degrees of elasticity and of which one is a waist belt and the other is an abdominal supporter and is bifurcated back and front to provide leg openings, and a strip of relatively inelastic fabric having 30 pointed ends secured to the edges of the bifurcations and provided with darts extending from the points of union of the edges of the bifurcations with the body of the strip providing a suspensory pouch.

HARRY C. GINGRICH.
